US00D979766S

(12) **United States Design Patent** (10) Patent No.: **US D979,766 S**
Stafford (45) Date of Patent: **** Feb. 28, 2023**

(54) **ANALYTE SENSOR DEVICE**(71) Applicant: **ABBOTT DIABETES CARE INC.**,
Alameda, CA (US)(72) Inventor: **Gary Ashley Stafford**, Hayward, CA
(US)(73) Assignee: **ABBOTT DIABETES CARE INC.**,
Alameda, CA (US)(***) Term: **15 Years**(21) Appl. No.: **29/777,142**(22) Filed: **Apr. 2, 2021****Related U.S. Application Data**

(63) Continuation of application No. 16/427,155, filed on May 30, 2019, which is a continuation of application No. 15/714,538, filed on Sep. 25, 2017, now Pat. No. 10,342,489, which is a continuation of application No. 15/271,991, filed on Sep. 21, 2016, now Pat. No. 9,775,563, which is a continuation of application No. 13/970,397, filed on Aug. 19, 2013, now Pat. No. 9,480,421, which is a continuation of application No. 11/240,259, filed on Sep. 30, 2005, now Pat. No. 8,512,243.

CLAIM

The ornamental design for an analyte sensor device, as shown and described.

DESCRIPTION

The FIGURE is a perspective view of an analyte sensor device showing my new design.

The dashed broken lines in the figures illustrate portions of the analyte sensor device that form no part of the claimed design.
